WILLIAM P. LARK, OF EASLEY, SOUTH CAROLINA

TRANSMISSION LINE CLAMP

Application filed March 28, 1929. Serial No. 350,789.

The present invention consists of a transmission line clamp, an object of which is to provide a cable suspension member which is adapted to hang the cable without the use of 5 snatch blocks or like hoisting means heretofore employed for engaging the cable with the conventional insulator clamp.

Another object of the invention is to provide a clamp in which the cable may be 10 hoisted and then tensioned, after which the cable is positively secured from movement or displacement.

A further object of the invention is to provide a transmission line clamp which may be utilized for hoisting the clamp to the insulator group and the cable stretched therethrough to the desired degree of tension, pursuant to which the cable may be clamped into a fixed position in a facile and expeditious 20 manner.

A still further object of the invention is to provide a clamp through which the cable may be stretched and afterwards secured, the clamp being equipped with highly conductive metal to increase conductivity at the same time reducing frictional resistance during the cable-tensioning operation to a minimum.

Other objects of the invention will be apparent from the following description of the present preferred form of the invention, taken in connection with the accompanying drawings, wherein

Fig. 1 is a side elevational view of a transmission line clamp constructed in accordance with the present invention, illustrating the application of the same;

Fig. 2 is a longitudinal sectional view of the line clamp, showing the cable line in dotted lines, and illustrating the clamp applied to the insulator arm, the latter being shown fragmentarily;

Fig. 3 is a vertical sectional view, taken on the line 3—3 of Fig. 2, looking in the direction of the arrow;

Fig. 4 is a vertical sectional view, taken on the line 4—4 of Fig. 2, looking in the direction of the arrow;

Fig. 5 is a vertical sectional view, taken on

the line 5—5 of Fig. 2, looking in the direction of the arrow; and

Fig. 6 is a plan view of the clamp plate.

In the drawings, in order to illustrate the application of the present invention, a portion 7 of the cross-arm of a line wire tower is shown, which is of conventional design, and is equipped on the free terminal with an eye 8. The eye pendently carries a group of discal insulators 9 from the lowermost of 60 which an arm 10 pends.

The clamp constructed in accordance with the present invention is generally designated 11 and embodies a frame or body portion and a clamping plate 12. The frame of the clamp 65 consists of parallel side plates 13, which are integrally connected through the medium of webs 14, the inner faces of the latter being concaved and preferably plated or otherwise equipped with a highly conductive film 15, 70 made of aluminum composition or like material. Transmission line receiving saddles are thereby provided. The webs 14 extend transversely across the frame and have a roller 16 mounted therebetween. Rollers 17 are 75 mounted between the plates 13 at the ends of the frame, beyond the outer terminals of the webs 14. The outer terminals of the frame extend downwardly beyond the rollers 17 to provide U-shaped guard members 18, for 80 a purpose more fully hereinafter set forth.

Each of the rollers 16 and 17 is preferably composed of a material of highly electrical conductivity, the bore of which is provided with a wear take-up sleeve 19, the latter 85 being keyed or otherwise fixedly secured to the roller. Each roller is adapted to be rotatably mounted on a shaft or axle 20, which is made of suitable wear-resisting metal, such as malleable steel, the shafts or axles being 90 fixedly secured to the frame. When the rollers are mounted in the frame it will be noted, especially upon reference to Fig. 2 of the drawings, that the vertices of the cable-impinging portions thereof are in a plane above 95 the plane of the plated web portions 14 of the frame. Consequently, when a transmission line cable, such as indicated at 21, is drawn through the clamp, the cable will pass 100 freely over the rollers clear of the plated

films or saddles 15. The provision of rollers permits the cable to be drawn through the clamp with a minimum resistance. After the cable has been drawn to the desired degree of tension, it may be clamped into fixed engagement with the plated webs 14 in a manner hereinafter set forth.

The clamp plate 12 is used for the purpose of urging the cable 21 into fixed engagement with the rollers 16 and 17 and the plated surfaces 15 of the webs 14. In order to urge the plate against the cable, hook bolts 22 are provided. The bill of each hook is adapted to rest in a complementary recess 23, which extends transversely across the outer face of the clamp. The shank of the bolt is screw-threaded as indicated at 24, and extends through the web 14 and is adapted for the reception of a nut 25. The nut 25 is threaded 20 on the shank of its bolt until it is engaged with the under face of one of the webs 14 or with a washer 26, which is interposed between the nut and the web to thereby draw the bill of the hook downwardly and correspondingly urge the clamp plate 12 inwardly so as to flex the cable 21 snugly in engagement with the plated films 15 of the webs 14. It will be noted that the inner face of the plate 12 is plated or provided with a covering 27 of highly conductive metal, such as aluminum composition. When the plate 12 is secured in position, as shown in the drawings, it will be noted that said cable is almost completely encased in the clamp between the bottom and sides of the frame and the clamp plate 12. When so clamped, the covering or plating 27 serves as a cushion for the cable 21. Consequently, possibility of cutting the strands of the cable or of corrosion of the latter, by contact with the rough steel clamp commonly used, is eliminated. The clamp plate is bowed midway its ends, as indicated at 28, to conform to the contour of the central roller 16, above which it is positioned. Consequently, when the plate 12 is urged inwardly against the cable 21 the latter is fixed from movement against the periphery of the roller 16.

The side plates 13 of the frame are provided with intermediate ears 29, which, as shown to advantage in Fig. 3, are arranged in parallel relation and are provided with openings therein which correspond with openings formed in the insulator arm 10 and are adapted for the reception of a bolt or pin 30 which is detachably engaged through said ears 29 and arm 10.

In engaging transmission line cables with group insulators on the cross-arms of line towers, it is customary to first engage the cable with a snatch block which is then hoisted into engagement with the eye 8 of the cross-arm, following which the cable is tensioned to the desired degree and then transferred to a clamp, consisting of a plate U-

shaped in cross-section, which is pendently supported by the insulator group. This procedure is both costly and laborious. With the present invention the use of snatch blocks is eliminated, since the clamp is directly engaged with the insulator group on the ground and the cable mounted in the clamp, after which the insulator group and clamp are hoisted into engagement with the eye 8 of the cross-arm, while the cable is slack. This hoisting operation is a simple one and may be performed by the use of an ordinary pulley block and a small expenditure of man-power. After the group of insulators and clamp constructed in accordance with the present invention is secured to the cross-arm, the cable is tensioned in a manner well known in the art, following which the cable is positively secured from displacement, in a manner already described. It is desirable to use in the clamp, material of high electrical conductivity which is usually a soft metal and consequently is subject to rapid wear by the frictional resistance set up when a cable is pulled therethrough. By the provision of rollers, as herein set out, the cable is drawn through the clamp with an almost complete absence of frictional resistance, since the cable, by reason of the peculiar positioning of the rollers, comes in contact with no part of the clamp body. However, by reason of the structure above described, when the cable is clamped from movement in the present invention, it is almost completely housed by a casing of high electrical conductivity, with obvious desirable advantages. Complete assemblage of the clamp and insulator group on the ground may be effected by use of the present invention, with the exception of the clamp plate 12, which may be inserted in the clamp body above the cable after the latter has been tensioned. It will be noted that the plates 13 are recessed, as indicated at 31, for the reception of the clamping bolts 22, the bills of the latter being adapted to rest in semi-circular recesses 32 which are formed in the upper margins of the plates 13, during the tensioning operation of the cable. As soon as the cable has been tensioned and the plate 12 positioned on top of the cable, the clamping bolts 22 are rotated so as to engage the bills of the bolts in the recesses 23 of the clamp plates, as heretofore described. The provision of the guards 18 prevent the cable from flexing downwardly, so as to also prevent drag against the rollers 17 during the tensioning operation of the cable. This further eliminates the possibility of any undue friction or wear on the rollers.

Although the present invention is shown as especially adapted for use with soft metal cable, it is nevertheless to be understood that the clamp is equally applicable for use with hard metal cable and correspondingly, the rollers, clamp body and clamp plate may be

made of hard metal throughout. The manner of associating the clamp with the insulator group and the theory of operation remains the same.

5 While I have herein described the present preferred form of the invention, it is nevertheless to be understood that various changes may be made in the invention, especially in the details of construction, proportion and arrangement of parts, within the scope of the
10 claims hereto appended.

What is claimed is:—

1. In a cable clamp for the insulators of transmission line towers, including a clamp embodying a plurality of uniplanar movable cable engaging parts, and means to clamp the cable against said parts.

15 2. In a cable clamp structure, mobile means to permit frictionless feeding of the cable therethrough, and means to urge the cable into fixed engagement with said means.

20 3. In a cable clamp for the insulator group of a transmission line tower, a clamp body equipped with rollers, cable seats formed in the body between said rollers, and means detachably mounted in the body to urge the cable into engagement with said rollers and seats.

25 4. A cable clamp including a clamp embodying cable seats, each of which is equipped with a plating of highly conductive metal, a series of rollers mounted in the clamp between said seats, and a clamping plate equipped with a plating of highly conductive material, said plate urging the cable into engagement with the seats and rollers.

30 5. A cable clamp including a clamp body equipped with a series of rollers and interposed cable seats, a clamp plate mounted in the clamp body over said seats and rollers, and means engageable through said clamp body and with the clamp plate for urging the latter in the direction of the seats and rollers.
